UNITED STATES PATENT OFFICE.

LOESER KALINA, OF BROOKLYN, NEW YORK.

KEY POCKETBOOK.

Application filed December 24, 1921. Serial No. 524,604.

To all whom it may concern:

Be it known that I, LOESER KALINA, a citizen of the United States, and a resident of the city of New York, borough of Brooklyn, in the county of Kings and State of New York, have invented a new and Improved Key Pocketbook, of which the following is a full, clear, and exact description.

The present invention relates to new and useful improvements in key-holders, and it pertains more particularly to key-holders of the enclosed type.

It is one of the primary objects of the invention to provide a new and improved form of key-holder in which the keys are completely enclosed.

It is a further object of the invention to so construct a key-holder that when the same is closed, the keys are kept free from dirt and the like.

It is a further object of the invention to provide a key holder which is entirely closed and so constructed that money or other articles carried in the same pocket with the key-holder will not be accidentally withdrawn upon the removal of the key-holder for the reason that said articles cannot enter the key-holder owing to the fact that the ends of the key receptacle are closed.

It is a further object of the invention to so construct a key-holder that when the same is opened, the keys will be automatically withdrawn from the key receptacle.

It is a still further object of the invention to construct a new and improved form of identification device adapted to be used in connection with key-holders.

Referring to the drawings,

Figure 1 is a view in elevation of a key-holder in open position;

Fig. 2 is a longitudinal sectional view taken on the line 2-2 of Fig. 1; and

Fig. 3 is a longitudinal sectional view of the key-holder in closed position.

Referring to the drawings, the device comprises a main body or body portion 5 to one end of which is secured a secondary body portion 6, by means of stitching or the like. This structure forms a pocket 8 in which the keys are adapted to be received when the holder is in closed position.

The main body portion or body 5 is extended as indicated by the reference character 9, and the lateral dimension of said extension 9 is slightly reduced with respect to the main body portion 5. Secured

to the free end of the extension 9, as by means of a row of stitching 10 or the like, is a flap 11, and said flap has its lower corners cut away as indicated by the reference character 12, said cutaway portion being unattached to the extension 9, as is also the lower edge 13. Adjacent this lower edge 13, the flap 11 is formed with a plurality of openings 14 and carried in each of said openings 65 is a key-hook 15 of the snap hook type. These key hooks are adapted to receive one or more keys 16 as shown in Figure 1.

The flap 11 is provided with a suitable sight opening 17 or window formed substantially centrally thereof, and owing to the line of stitching 10, said flap is adapted to maintain an identification card 18, positioned behind said sight opening in such a manner that the indicia carried by said card 75 will be displayed through said sight opening 17.

The extension 9 is provided with a socket 20 and secured to the secondary body portion 6 is the head 21 of a head-and-socket 80 fastener, said head being adapted to be engaged in the socket to retain the device in closed position.

The device operates in the following manner:

When the device is closed as indicated in Fig. 3, the several keys 16 occupy a position behind the body portion 6 with the extension 9 serving as the closure for the pocket. When, however, the head-and-socket fastener are disengaged and the extension moved to the position shown in Fig. 1, the keys will be elevated to the position shown in said figure, where they are free to be removed from behind the body portion 6, 95 through the cut-out portion thereof.

By this construction it is apparent that as the device is opened, the keys are automatically withdrawn from the pocket in which they are contained when the device is 100 closed, and upon the closing of the closing flap of the device, the keys are automatically positioned within the pocket between the main body portion 5 and the secondary body portion 6, where they will be protected from 105 dirt or other accumulations in the pocket of the user.

I claim:

1. An article holder comprising a pair of members adapted to fold together to enclose 110 articles therebetween, and article attaching devices carried by one of said members and

adapted to move the articles carried thereby relative to the other member upon movement of the members to open or closed position.

2. As a new article of manufacture, a key holder comprising a main body portion, an auxiliary body portion secured thereto in spaced relation with the main body portion to provide a key-receiving pocket, an extension formed on the main body portion and 10 adapted to serve as a closing flap for said pocket, and a plurality of key-supporting members carried by said flap in such a manner that as the flap is opened, the keys will be automatically withdrawn from the 15 pocket.

3. As an article of manufacture, a key-holder comprising a main body portion formed with a pocket, an extension serving as a closing flap, an auxiliary flap secured to 20 said extension and provided with a window opening adapted to display indicia carried by a card at the rear of said auxiliary flap, and a plurality of key-supporting hooks carried by said auxiliary flap.

25 4. As a new article of manufacture, a key holder comprising a main body portion formed with a key-receiving pocket, a reduced extension of the body portion formed thereon and providing a closing flap for said 30 pocket, an auxiliary flap secured to said ex-

tension on the inner face thereof, said auxiliary flap having a plurality of perforations along one of its edges, and a plurality of key-supporting elements mounted in said perforations, substantially as described.

35 5. As a new article of manufacture, a key-holder comprising a main body portion formed with a pocket, an extension forming a flap adapted to close said pocket, and means for supporting a plurality of keys from said flap in such a manner that as the flap is closed, the keys will automatically assume a position within the pocket, and when the flap is opened, the keys will be automatically withdrawn from the pocket.

40 6. A device for holding keys and the like comprising a body portion adapted to receive keys or the like, a closure movably associated with said body portion, and key-attaching devices carried by said closure whereby the keys are withdrawn from said body portion on the opening of the closure, and are advanced into the same on movement of the closure to closed position.

45 7. In an article holder, a body portion having an article receiving pocket, a hinged closure therefor, and article attaching means carried by the closure at the side of the hinge line thereof remote from the said body.

50 LOESER KALINA.
